(57) **CLAIM**

The ornamental design for a convertible trolley and table, as shown and described.

DESCRIPTION

FIG. 1 is a front, top, and right side perspective view of a convertible trolley and table showing our new design, shown in a trolley position;

FIG. 2 is a front view, shown in the trolley position;

FIG. 3 is a rear view thereof, shown in the trolley position;

FIG. 4 is a left side view thereof, shown in the trolley position;

FIG. 5 is a right side view thereof, shown in the trolley position;

FIG. 6 is a top view thereof, shown in the trolley position;

FIG. 7 is a bottom view thereof, shown in the trolley position;

FIG. 8 is a rear, top, and left side perspective view thereof, shown in a table position;

FIG. 9 is a front view thereof, shown in the table position;

FIG. 10 is a rear view thereof, shown in the table position;

FIG. 11 is a left side view thereof, shown in the table position;

FIG. 12 is a right side view thereof, shown in the table position;

FIG. 13 is a top view thereof, shown in the table position;

FIG. 14 is a bottom view thereof, shown in the table position;

FIG. 15 is a rear, top, and left side perspective view thereof, shown in a folded position;

FIG. 16 is a front view thereof, shown in the folded position;

FIG. 17 is a rear view thereof, shown in the folded position;

FIG. 18 is a left side view thereof, shown in the folded position;

FIG. 19 is a right side view thereof, shown in the folded position;

FIG. 20 is a top view thereof, shown in the folded position;

and,

(Continued)

FIG. 21 is a bottom view thereof, shown in the folded position.
